UNITED STATES PATENT OFFICE.

WALLACE MOHR, OF OKLAHOMA, OKLAHOMA.

TONGUE-TRUCK.

No. 888,251.

Specification of Letters Patent.

Patented May 19, 1908.

Application filed June 6, 1907. Serial No. 377,529.

To all whom it may concern:

Be it known that I, WALLACE MOHR, a citizen of the United States, and a resident of Oklahoma city, in the county of Oklahoma, Oklahoma, have invented a new and Improved Tongue-Truck, of which the following is a full, clear, and exact description.

This invention relates to tongue trucks, and more particularly to that class of tongue trucks adapted to be used in connection with agricultural machinery such as harvesters, binders and the like.

The object of the invention is to provide a simple, strong and efficient tongue truck, for supporting the weight of the tongue and preventing side draft of the vehicle when the latter is in motion.

A further object of the invention is to provide a device of the class described, comprising a member secured to the vehicle at an angle therewith and carrying the truck, and a tongue normally in the line of draft, carried at an angle with the member, whereby it is possible to hitch the draft animals comparatively close to the vehicle.

A still further object of the invention is to provide a tongue truck having wheels adapted to be laterally displaced by the movement of the tongue, the arrangement being such that the lateral angular movement of the tongue effects a greater lateral or angular displacement of the wheels, whereby the machine can be guided in turning and in similar movements, with great facility.

The invention consists in the construction and arrangement of parts to be more particularly described hereinafter and fully set forth in the claims.

Reference is to be had to the accompanying drawings forming a part of this specification, in which similar characters of reference indicate corresponding parts in all the views, and in which

Figure 1 represents a plan view of my invention; Fig. 2 is a similar view showing parts in different positions; Fig. 3 is a side elevation of my invention; Fig. 4 is an enlarged side elevation of a part of the invention showing certain portions in vertical cross-section; Fig. 5 is a front elevation of the tongue truck showing a part in cross-section; Fig. 6 is a vertical cross-section of a wheel; and Fig. 7 is an elevation showing a detail of a modified form.

Before proceeding to a more detailed ex-

planation of my invention, it should be understood that it is frequently a matter of great difficulty properly to secure the draft animals to agricultural machinery such as harvesters, reapers, binders and the like, in which the vehicle embodied in the machine is cumbersome in form and difficult to maneuver. Naturally, if the draft animals are secured close to the vehicle the latter is handled with less difficulty; but hitching the animals in such manner may entail danger from the moving machinery, to the animals, or may render it impossible to execute short turns. To obviate these difficulties I provide a tongue truck, secured to the vehicle by means of a rigid member comprising a stub tongue mounted upon the vehicle and having a brace extending at an angle therewith and also secured to the vehicle. The guide tongue is mounted upon the brace and lies normally in the line of draft and is arranged at an angle with the stub tongue. The stub tongue carries the truck, which consists of one or more wheels adapted to be laterally displaced. I provide means for operatively connecting the wheels and the draft tongue, so that when the latter is displaced angularly the wheels are similarly displaced in the same direction but to greater angles. By means of this arrangement it is possible to turn the vehicle with ease and at a sharper angle, without turning the draft animals as far in the direction of the lateral movement of the vehicle as the vehicle itself is turned. By securing the draft animals close to the vehicle it is easier for the driver to control the same; however, if they are too close they are liable to be injured by coming in contact with the harvester reel, for instance, or the cutting mechanism. This danger is obviated in my invention, as the animals need be swung through a smaller angle than the angle through which the vehicle itself turns.

Referring more particularly to the drawings, Fig. 1 represents a tongue truck member, or stub tongue, secured by means of a suitable bracket 2, to the vehicle 3 comprising the agricultural machine, the vehicle presenting an extension 4 at which the bracket 2 is mounted by means of a pivot bolt 5. The stub tongue 1 is arranged at an angle with the line of draft and preferably extends at an angle upward, being mounted close to the ground at the end secured to the vehicle. A bar 6 of iron or other suitable material, has

one end secured to the stub tongue 1 near the forward end, by means of bolts 7, is outwardly offset, and secured near the opposite end of the stub tongue by means of bolts 8, 5 the end of the bar 6 beyond the bolts 8 being laterally disposed substantially parallel to the vehicle. A second bar 9 has an end secured to a flat portion 10 of the bar 6 at the point where it is offset from the stub tongue 1, and has an opposite end secured to the end 10 of the bar 6 by means of a rivet 11 and extending therebeyond, pivoted in a bracket 12 carried by the vehicle 3 by means of a bolt 13. The bar 9 is secured to the part 10 of the bar 15 6 by means of rivets 14 and has the extremity formed into a bearing 15. A pivot pin 16 is arranged in the bearing 15 and carries a bracket 17. The bracket 17 is pivotally arranged in a recess 19 of the guide tongue 18 and is secured in position by means of a pivot 20 pin 20. The guide tongue 18 is arranged at an angle with the stub tongue 1 and normally lies in the line of draft of the vehicle. The stub tongue and the brace can swing vertically about their horizontal pivots.

25 A socket 21, having an inclined upper face presenting a lateral flange 22, is secured at the under side of the stub tongue 1, near the free end of the same, by means of bolts 23 30 passing through suitable openings in the flange 22. The socket 21 has a suitable opening or hole 24 for a purpose which will appear hereinafter, and strengthening integral ribs 25 at the sides. The forward portion of the socket at the lower edge is cut away and presents shoulders 26. A substantially vertical shaft 27 has the upper end rigidly mounted in the opening 24 of the socket and has the lower end formed into a laterally-disposed arm 28. A sleeve 29 is arranged upon the shaft 27 and is free to rotate thereupon. The sleeve 29, near the upper end, has a laterally-extending arm 30 and similarly, at the lower end, has a laterally-extending arm 31, shorter than the arm 30. 35 The arm 30 has an integral stop 32 for a purpose which will appear hereinafter. A bracket 33, having a suitably formed recess 34, is pivotally arranged upon the arm 28 of the shaft 27, the sleeve 29 seating against the upper end of the bracket 33, which has at the lower side lateral extensions 35. The arm 28 extends through the opening of the bracket and is secured in position by means 45 of a transverse pin 36. At the under side the bracket 33 has a rounded recess 37 which seats upon a transverse shaft 38, and upon which it is secured by means of bolts 39 arranged in suitable openings in the shaft 38 and the bracket 33. The upper face of the socket 21 is suitably inclined to permit the stub tongue 1 to rest evenly thereupon as is shown most clearly in Fig. 4.

50 The extremities of the transverse shaft 38 65 are upwardly disposed and constitute pivot

pins 40, upon which are rotatably mounted axles 41, having suitable vertical openings for the purpose. The axles 41 carry wheels 42 having hubs 43 and peripheral flanges 44. The purpose of the flanges is to permit the 70 wheels to grip more firmly in soft ground such as that of a plowed field, and to prevent side movement of the wheels. The hubs 43 extend beyond the wheels at one side, and the spokes 45 of the wheels are inclined 75 towards the extending ends of the hubs to permit the wheels to be set as close as possible to the pins 40. The axles have-collars 46 arranged upon the pins and are secured in position by transverse stop pins 47. The axles 80 further have forwardly extending integral arms 48 having openings. The arms 48 are operatively connected by means of links 49 with the arm 31 of the sleeve 29. The links having the ends laterally and oppositely disposed are pivotally arranged in the openings of the arms 48 and in similar openings of the arm 31. The ends of the links which are pivoted upon the arm 31 are secured in position by means of transverse pins 50.

85 An eye-bolt 51 is carried by the guiding tongue 18, and operatively connected by means of a link 52 having eyes 53 and 54, with the arm 30 of the sleeve 29. The arm 30 has a suitable opening 55, at the end of 90 which is arranged the eye 54 of the link 52; the eye 53 of the latter being mounted at the eye of the eye-bolt 51. The arrangement is such, that the distance between the pivotal point of attachment of the guiding tongue 95 and the point of attachment of the link 52 at the tongue 18, is greater than the length of the arm 30, so that when the guiding tongue is laterally displaced through a certain angle, the arm 30 will be displaced in the same direction, but through a greater angle, owing to its shorter length. It will be understood that as the arm 30 is moved to one side or the other, the arms of the axles are similarly displaced through the connecting arms and 100 links, the arrangement being such that the wheels are moved through an angle considerably greater than the angle through which the guiding tongue is moved. The movement of the arm 30 is limited by the shoulders 105 26 of the socket, the stop 32 of the arm 30 engaging the shoulders to limit the movement. The socket rests upon the stop and the upper end of the sleeve as is shown most clearly in Fig. 4.

110 The tractive power is applied at the end of the stub tongue 1 by means of a whiffle-tree 56, which is secured at the end of the stub tongue in the usual manner, by means of an offset bracket 57 and bolt pin 58. By means of the whiffle-tree, horses or other draft animals can be hitched to the agricultural machine for the purpose of moving it from place to place. The end of the whiffle-tree adjacent to the tongue is secured to the latter by 115 120 125

means of a chain 65 and a bolt 66 more efficiently to apply the tractive power. When the tractive power is supplied by draft animals, the pull is exerted upon the end of the 5 member 1 and so transmitted to the vehicle. The animals nearest to the tongue 18 are secured thereto in such a manner, that when the driver desires to guide the machine to one side or the other the movement of the 10 animals in that direction will correspondingly turn the tongue in the same direction. The lateral movement of the tongue is transmitted through the connecting links to the wheels which travel along the ground, and 15 in consequence of the lateral movement of the tongue the wheels are partly rotated about a vertical axis. By thus laterally disposing the guide wheels, the direction of the movement of the entire vehicle is quickly and 20 easily altered. This is especially true if the ground is heavy and the flanges of the wheels are sunk into it somewhat, for in this case there is absolutely no skidding or lateral sliding of the wheels.

25 I prefer to provide my device with a truck and two guide wheels; if so desired, however, the truck may be dispensed with and a single guide wheel employed as is shown in Fig. 7. In this case the guide wheel has a 30 peripheral flange 65^a at the center of its rim and is rotatably mounted between the sides of the fork 59. The sleeve 60 in this case has but one lateral arm 61 to which is secured the connecting link 52, joining it 35 with the tongue 18; the sleeve is rigid with the shaft 62 which is pivotally mounted in the socket 63. Thus the lateral displacement of the tongue 18 is transmitted directly to the single wheel 64 through the connecting link 52.

40 It is of advantage to have the tongue truck hinged to the vehicle, in the case of a harvester, for instance, as it is necessary to permit the harvester to be tilted into different positions in harvesting grain of various lengths.

Having thus described my invention, I claim as new and desire to secure by Letters Patent:

50 1. A device of the class described, comprising a vehicle, a member adapted to be movably mounted upon said vehicle and having a brace, a tongue pivotally mounted upon said brace, a wheel arranged at the 55 end of said member, and means for controlling said wheel by the movement of said tongue.

2. A device of the class described, comprising a vehicle, a member adapted to be pivotally secured to said vehicle, a brace connecting said vehicle and said member, a tongue pivotally mounted upon said brace, a wheel mounted at the end of said member and adapted to be laterally displaced, and means for laterally displacing said wheel by 65 the movement of said tongue.

3. A device of the class described, comprising a vehicle a member adapted to be pivotally secured to said vehicle and having a truck, a brace pivoted to said vehicle and secured to said member, a tongue pivotally mounted upon said brace, a wheel mounted at the end of said truck and adapted to be laterally displaced, and means for laterally displacing said wheel by the movement of said tongue. 70

4. A device of the class described, comprising a vehicle a member adapted to be pivotally secured to said vehicle and having a truck, a brace pivoted to said vehicle and secured to said member, a tongue pivotally mounted upon said brace, a wheel mounted at the end of said truck and adapted to be laterally displaced, and a link having pivotal connection with said wheel and said tongue and adapted laterally to displace said wheel 80 by the lateral movement of said tongue. 85

5. In a device of the class described, a vehicle, a member adapted to be pivotally secured to said vehicle and arranged at an angle to the line of draft of said vehicle, said 90 member having a truck, a brace pivoted to said vehicle and secured to said member, a tongue pivotally mounted upon said brace, a wheel mounted at the end of said truck and adapted to be laterally displaced, and 95 means for laterally displacing said wheel by the movement of said tongue.

6. In a device of the class described, a vehicle a member adapted to be pivotally secured to said vehicle and arranged at an 100 angle with the line of draft of said vehicle, said member having a truck, a brace pivoted to said vehicle and secured to said member, a tongue pivotally mounted upon said brace, a wheel mounted at the end of said truck 105 and adapted to be laterally displaced, and a link having a pivotal connection with said wheel and said tongue and adapted laterally to displace said wheel by the lateral movement of said tongue. 110

7. In a device of the class described, a vehicle a member adapted to be pivoted to said vehicle to swing vertically and having a truck, a brace pivoted to said vehicle to swing vertically and secured to said member, a tongue pivotally mounted upon said brace, a wheel mounted at the end of said truck and adapted to be laterally displaced, and means for laterally displacing said wheel by the movement of said tongue 120 through an angle greater than the angular displacement of said tongue. 115

8. In a device of the class described, a vehicle a member mounted upon said vehicle to swing vertically and having a truck, a brace pivoted to said vehicle to swing vertically and secured to said member, a tongue pivotally mounted upon said brace, a wheel mounted at the end of said truck and adapted 125 to be laterally displaced, and a link having 130

pivotal connection with said wheel and said tongue and displacing said wheel by the lateral movement of said tongue through an angle greater than the angular displacement 5 of said tongue.

9. In a device of the class described, a vehicle a member adapted to be pivoted to said vehicle to swing vertically and arranged at an angle with the line of draft of said 10 vehicle, said member having a truck, a brace pivoted to said vehicle to swing vertically and secured to said member, a tongue pivotally mounted upon said brace, a wheel mounted at the end of said truck and 15 adapted to be laterally displaced, and means for laterally displacing said wheel by the movement of said tongue through an angle greater than the angular movement of said tongue.

20 10. In a device of the class described, a vehicle a member adapted to be pivoted to said vehicle to swing vertically and arranged at an angle with the line of draft of said vehicle, said member having a truck, a brace 25 pivoted to said vehicle to swing vertically and secured to said member, a tongue pivotally mounted upon said brace, a wheel mounted at the end of said truck and adapted to be laterally displaced, and a link having 30 pivotal connection with said wheel and said tongue and laterally displacing said wheel by the lateral movement of said tongue through an angle greater than the angular movement of said tongue.

35 11. In a device of the class described, a vehicle a member adapted to be pivoted to said vehicle to swing vertically and having a truck near one end thereof, a brace pivoted to said vehicle to swing vertically and secured to said member, said truck having vertical pins, axles pivotally mounted upon said pins, wheels mounted upon said axles, arms rigid with said axles, a tongue pivotally mounted upon said brace, links pivotally 45 secured at the ends of said arms, and a connecting bar joining said links and said tongue.

12. In a device of the class described, an agricultural machine a member adapted to be horizontally pivoted to said agricultural 50 machine and having a truck, a brace horizontally pivoted to said machine and secured to said member, a tongue pivotally mounted upon said brace, wheels mounted at the ends of said truck and adapted to be laterally displaced, links having a pivotal connection 55 with said wheels, and a connecting bar pivotally connected with said links and with said tongue.

13. In a device of the class described, a 60 vehicle, a member adapted to be pivoted to said vehicle and having a shaft, a pivoted tongue, a truck pivotally mounted upon said shaft, a sleeve having rigid arms, said sleeve pivotally mounted upon said shaft, 65 said truck having laterally extending pins

near the ends thereof, axles rotatably mounted upon said pins and having wheels, arms rigid with said axles, links connecting said arms of said axles with an arm of said sleeve, and a connecting bar pivotally 70 mounted upon another of said arms of said sleeve and upon said tongue.

14. In a device of the class described, a vehicle, a member adapted to be pivotally secured to said vehicle and having a shaft, a 75 brace secured to said member and to said vehicle, a tongue pivotally mounted upon said brace, a truck carried by said shaft, said shaft having a movable member provided with arms, a transverse shaft having lateral 80 extensions near the ends thereof, axles rotatably mounted upon said extensions and having wheels, arms rigid with said axles, links connecting said arms of said axles with an arm of said member upon said shaft, and 85 a connecting bar pivotally secured to said tongue and to another of said arms of said member upon said shaft.

15. In a device of the class described, a vehicle a member adapted to be secured to 90 said vehicle to swing vertically and having a socket, a shaft having an end rigidly mounted in said socket, a sleeve having laterally disposed arms arranged free to rotate upon said shaft, a transverse shaft secured to said first 95 shaft and having upwardly disposed ends, axles having arms mounted to pivot upon said ends of said transverse shaft, wheels upon said axles, links connecting said arms of said axles with one of said arms of said 100 sleeve, a tongue connected with said member, and a link connecting said tongue and another arm or said sleeve, said member being arranged at an angle with the line of draft of said vehicle, said tongue being arranged at an angle with said member. 105

16. In a device of the class described, a vehicle a stub tongue adapted to be pivoted to said vehicle and having a truck, a brace adapted to be pivoted to the vehicle and 110 secured to said stub tongue, said stub tongue being arranged at an angle with the line of draft of the vehicle, a guide tongue pivotally mounted upon said brace, a wheel mounted upon said truck and adapted to be laterally 115 displaced, a pivoted arm, means for controlling said wheel through the movement of said arm, and operating means connecting said arm and said draft tongue, the length of said draft tongue between the point of attachment thereof and the point of attachment thereto of said operating means, exceeding the length of said arm. 120

In testimony whereof I have signed my name to this specification in the presence of 125 two subscribing witnesses.
